UNITED STATES PATENT OFFICE.

JAMES E. PALMER, OF ATLANTIC CITY, NEW JERSEY.

VENTILATOR.

1,358,240.

Specification of Letters Patent.

Patented Nov. 9, 1920.

Application filed February 9, 1920. Serial No. 357,491.

To all whom it may concern:

Be it known that I, JAMES E. PALMER, commander, U. S. Navy, retired, and a citizen of the United States, residing at present 5 at Atlantic City, in the county of Atlantic and State of New Jersey, have invented certain new and useful Improvements in Ventilators; and I do hereby declare the following to be a full, clear, and exact description 10 of the invention, such as will enable others skilled in the art to which it appertains to make and use the same.

This invention relates to ventilators, especially adapted for rooms having windows 15 and radiators, and has for its object to provide an apparatus of this kind which will be inexpensive to construct, and more efficient in action than those heretofore proposed.

With these and other objects in view the 20 invention consists in the novel details of construction and combinations of parts more fully hereinafter disclosed and particularly pointed out in the claims.

Referring to the accompanying drawings 25 forming a part of this specification in which like numerals designate like parts in all the views:—

Figure 1 is a diagrammatic plan view of a 30 ventilator made in accordance with this invention; and

Fig. 2 is a sectional view on the line 2—2 of Fig. 1, looking in the direction of the arrows.

1 indicates a window or other opening for 35 fresh air, 2 the sash or frame, 3 the opening through which air enters the room 4, 5 a window sill or other portion of the walls of room 4, 6 any suitable frame or conduit for conveying air from opening 3 into said room 40 4, 7 a delivery opening from said conduit adapted to deliver the cold air between the wall 8 and a radiator or other source of heat 9, and 10 a shield, casing or deflector adapted to partially surround the radiator 9, and 45 prevent the cold air from creating a draft along the floor 11.

12 indicates a loose board, a piece of felt, or other suitable means adapted to overlie the top 13 of the conduit 6, and to bridge 50 the space 14 between said top and the window pane 15, and thus prevent the cold air from escaping through said space 14.

Said felt 12 conveniently fits against the pane 15 while not preventing the ready 55 opening and closing of the window 1.

It will thus be seen that in operation, my

invention receives cold air through opening 3, delivers it into the room at the top of and behind the radiator 9, and forces it to descend down into the space 17 between the 60 said radiator and wall, where it is more or less heated up and whence it being heavier than the warm air of the room, it finds its way into the well or pocket 18 formed by the deflector or casing 10, fitting the floor and 65 compelling said air to ascend, all as is indicated by the arrows.

The pressure of the oncoming air, as well as the heat imparted to it from the radiator will cause said cold air to diffuse itself from 70 the space 17 and from the pocket 18 out into the room without producing the objectionable drafts that are found to accompany the use of certain other ventilators of well known types.

The entire frame or conduit 6 is readily attached to and detached from the window sill 5. In fact it may be fashioned to fit said sill, and permanently fastened thereto, or it may be merely loosely placed in position 80 and held in place by gravity.

It is obvious that those skilled in the art may vary the details of construction as well as the arrangement of parts without departing from the spirit of the invention, and 85 therefore, I do not wish to be limited to the above disclosure except as may be required by the claims.

What I claim is:—

1. In a ventilator for a room, the combination of a vertically disposed source of heat; means to provide a space for cold air in close proximity to said source of heat; a readily removable conduit provided with means for delivering cold air near the top of said source of heat and into said space; and means associated with said space and source of heat constituting a well to receive said air and adapted to prevent said cold air from forming drafts along the floor of the room, substantially as described.

2. In a ventilator, for a room, the combination of a source of heat; means comprising a confining wall surface to provide a space for cold air in close proximity to said source of heat; a readily removable conduit adapted to fit a window sill provided with means for delivering cold air at the top of said source of heat and into said space; and means comprising a casing fitting the floor 100 associated with said space and source of heat adapted to prevent said cold air from 105 110

forming drafts along the floor of the room, substantially as described.

3. In a window ventilator for a room provided with a radiator the combination of a conduit adapted to fit the window sill, and having an exit means adapted to deliver cold air into said room at the top of and behind said radiator when said window is open; means fitting the floor to constitute a well to receive said cold air and a flexible member extending from said conduit to said window adapted to prevent the escape of said air through the space between said conduit and said window, substantially as described.
- 10 4. In a room ventilating means the com-

bination of a radiator spaced from a wall of said room; a window opening into said room; a readily movable conduit fitting the window sill provided with an exit located at the top of said radiator and adapted to 20 deliver cold air from said window into the space between said radiator and wall; flexible means to prevent the leakage of air between said window and conduit; and means fitting the floor to form a well, and partially 25 encircling said radiator to prevent drafts on the floor of said room, substantially as described.

In testimony whereof I affix my signature.

JAMES E. PALMER.
